UNITED STATES PATENT OFFICE.

PASHER W. WATSON, OF SELBYVILLE, DELAWARE.

BURIAL-VAULT.

1,365,806.

Specification of Letters Patent. Patented Jan. 18, 1921.

Application filed June 24, 1920. Serial No. 391,333.

To all whom it may concern:

Be it known that I, PASHER W. WATSON, a citizen of the United States, residing at Selbyville, in the county of Sussex and State 5 of Delaware, have invented certain new and useful Improvements in Burial-Vaults, of which the following is a specification, reference being had to the accompanying drawings.

10 This invention relates to coffin receptacles and more particularly to a cement burial vault.

An important object of the invention is to provide a burial vault of this type which 15 is thoroughly air and water proof.

The invention has for a further object, the provision of a burial vault of this kind which has means for supporting a casket therein in spaced relation to the bottom of 20 the vault, thereby permitting circulation of air beneath the coffin and effectually preventing the formation of moisture which will cause deterioration.

Other objects and advantages of the invention will become apparent throughout 25 the course of the following description.

In the accompanying drawings, wherein for the purpose of illustration is shown a preferred embodiment of my invention and 30 wherein like reference characters designate like parts throughout:

Figure 1 is a longitudinal sectional view of a burial vault constructed in accordance with my invention.

35 Fig. 2 is a transverse sectional view thereof.

Referring now more particularly to the drawings, the numeral 10 indicates a receptacle for a casket which is provided with 40 a closure or cover 11.

The receptacle 10 comprises a base 12 having side and end walls 13 formed integrally therewith and preferably of some suitable plastic material such as Portland cement 45 of a good quality and which is waterproof. The sides and ends 13 at the point of junction of the base are provided with enlargements 14 for the purpose of reinforcing the base to eliminate the breaking common

50 at this point, the enlargement preferably taking the form of a panel. The outer faces of the side and end walls bulge outwardly adjacent the top thereof as at 16 and the upper face of the bulge is provided with 55 a horizontal portion 17 extending entirely around the vault. This horizontal portion 17

is arranged in a different horizontal plane from that of the horizontal sections 15 and the material of the side and ends intermediate the portions 15 and 17 is concaved 60 as at 18, having the lowest point of the concavity arranged nearer the lowermost of the surfaces 15 and 17, thereby providing adjacent such lowermost point upwardly inclined surfaces 18' of considerable length. 65

The cover or closure 11 is provided upon the inner side of the under surface of its edge with a horizontal surface 19 adapted to coact with the horizontal surfaces 15, and upon the outer side of the under surface of 70 its edges with a horizontal surface 20 adapted to coact with the horizontal surface 17. Intermediate these horizontal surfaces 19 and 20 the material of the edges of the top is convexed downwardly to coact with the concavity 18 of the side and end walls 13. 75

The under surface of the cover 11 is upwardly concaved in transverse section as indicated at 22, this concavity being continued to form at the ends of the cover straight 80 walls 23 permitting the use within the vault of a full size, or slightly over size casket. The cover 11 is provided with handles 24 embedded in the material thereof for convenience in placing the same in position and 85 is suitably reinforced as at 25.

The receptacle 10 is provided in the base and side walls thereof with a layer of reinforcing material 26, such as galvanized wire or the like, this reinforcing being bifurcated toward the upper ends of the side and end walls to form arms 27 and 28 extending into and adjacent to the surfaces horizontal portions 17 and 15, effectually preventing breakage of the bulge formed 95 of the swelling 16. The base of the receptacle 10 is provided interiorly with transversely arranged spaced ribs 29 for the purpose of spacing the base of the casket in the face 12, in order that proper ventilation 100 may be had to prevent collection of moisture.

In the use of my vault, subsequent to the placing of the casket therein, sealing material 20 is placed in the concavity 18 which 105 forms a receptacle therefor. The cover 11 is then placed in position, the placement is rendered extremely easy by the bag shape of the coacting edges of the receptacle and cover. The sealing material 30 is squeezed 110 out of the concavity 18, by the convex portion 21 of the lid onto the inclined wall 18'

and horizontal surfaces 15 and 17, and forms a tight seal between the abutting edges of the lid and the receptacle. The lid 11 is preferably made of such length and width 5 with the outer edges 31 projecting beyond the outer edges of the swelling 16 in order to prevent collection of water in the adjacent edges therefor. If desired, sealing material may be placed beneath the overhang formed 10 by this extended lip 31 as at 32, further assuring the sealing of the vault.

As many changes are possible in the shape, size and general arrangement of the various parts herein shown, I do not limit myself to 15 the specific structure hereinbefore set forth, but may make any such changes, without departing from the spirit of the invention or the scope of the subjoined claims.

Having now described my invention, 20 what I claim is:

1. In a burial vault a receptacle embodying side and end walls provided upon the upper ends thereof with enlargements, said enlargements being provided upon the 25 upper surface thereof with outer and inner horizontal faces disposed in different horizontal planes, a downwardly concaved groove formed intermediate said horizontal surfaces and adapted to receive a sealing medium, said groove having its greatest 30 depth at a point nearest the lowermost of said horizontal surfaces thereby providing an inclined surface of considerable length connecting the point of greatest depth of the 35 groove to the uppermost of said horizontal surfaces, and a cover for said receptacle provided upon its under surface of its outer edges with an irregular surface complemen-

tary to the upper surface of said side and end walls, the inclination of said inclined 40 surface being sufficient to permit squeezing of the sealing medium placed within the groove upon said inclined surface when the cover member is placed in position.

2. In a burial vault a receptacle embodying side and end walls provided upon the upper ends thereof with outer and inner horizontal faces disposed in different horizontal planes, the inner horizontal surface being uppermost, a downwardly concaved 50 groove formed intermediate said horizontal surfaces and adapted to receive a sealing medium, said groove having its greatest depth at a point nearest the outer horizontal surface thereby providing an inclined 55 surface of considerable length connecting the point of greatest depth of the groove to the inner horizontal surface, and a cover for said receptacle provided upon its under surface of its outer edges with an irregular 60 surface complementary to the upper surface of said side and end walls, the inclination of said inclined surface being sufficient to permit squeezing of the sealing medium placed within the groove upon said inclined 65 surface when the cover is placed in position, said cover being of greater width and length than the portion of the receptacle which it engages whereby said vault when assembled is provided with an overhanging 70 lip at the junction of the receptacle and cover.

In testimony whereof I hereunto affix my signature.

PASHER W. WATSON.
